UNITED STATES PATENT OFFICE.

PATRICK LEE HUDGINS, OF DECATUR, GEORGIA.

DESIGN FOR AN AUTOMOBILE-TOOL.

55,792.

Specification for Design.

Patented July 13, 1920.

Application filed March 5, 1920. Serial No. 363,567. Term of patent 14 years.

To all whom it may concern:

Be it known that I, PATRICK LEE HUDGINS, a citizen of the United States, residing at Decatur, in the county of Dekalb and State of Georgia, have invented a new, original, and ornamental Design for an Automobile-Tool, of which the following is a specification, reference being had to the accompanying drawings, forming part thereof.

Figure 1 is a perspective view of the tool showing my new design; and

Fig. 2 is a side elevation of the tool shown in Fig. 1.

I claim as my invention:

The ornamental design for an automobile tool as shown.

In testimony whereof, I affix my signature.

PATRICK LEE HUDGINS.
